(57) CLAIM

The ornamental design for a two-slot adapter for motorcycle-to-trike conversion kit, as shown and described.

DESCRIPTION

FIG. 1 is a perspective view of the two-slot adapter for motorcycle-to-trike conversion kit according to the present invention.

FIG. 2 is a front view of the two-slot adapter for motorcycle-to-trike conversion kit according to the present invention. The rear view is a mirror image of the front view.

FIG. 3 is a right side view of the two-slot adapter for motorcycle-to-trike conversion kit according to the present invention.

FIG. 4 is a left side view of the two-slot adapter for motorcycle-to-trike conversion kit according to the present invention.

FIG. 5 is a top view of the two-slot adapter for motorcycle-to-trike conversion kit according to the present invention; and,

FIG. 6 is a bottom view of the two-slot adapter for motorcycle-to-trike conversion kit according to the present invention.

The broken lines in all views are for illustrative purposes only and form no part of the claimed design.
